CLAIM

The ornamental design for a variable length putter shaft, as shown and described.

DESCRIPTION

FIG. 1 is a perspective view of a variable length putter shaft showing my new design;

FIG. 2 is a front elevational view thereof, the undisclosed opposite sides being identical;

FIG. 3 is a front elevational view with the shaft shown in an extended position for clarity of illustration;

FIG. 4 is a top plan view of FIG. 2; and,

FIG. 5 is a bottom plan view of FIG. 2.

The broken line showing of a golf putter head is for illustrative purposes only and forms no part of the claimed design.
